UNITED STATES PATENT OFFICE.

FRANK B. HART AND THOMAS G. VAN SANT, OF POPLAR BLUFF, MISSOURI.

REFRIGERATOR OR ICE-BOX.

1,239,481.

Specification of Letters Patent. Patented Sept. 11, 1917.

Application filed May 29, 1915. Serial No. 31,228.

To all whom it may concern:

Be it known that we, FRANK B. HART and THOMAS G. VAN SANT, citizens of the United States, residing at the city of Poplar Bluff, Butler county, State of Missouri, have invented a new and useful Refrigerator or Ice-Box, of which the following is a specification.

This invention relates to refrigerators or 10 ice boxes.

An object of the invention is to provide a refrigerator or ice box including a compartment for the ice, having therein a supporting grate or frame for the ice, in combination with a series of pivoted levers of novel construction and arrangement upon which said grate or frame is mounted, and a visible indicator under control of said levers for indicating the quantity or the weight of the 20 ice continuously, whereby the user may at all times be informed of the quantity of ice placed within or removed from the compartment.

Another object is to provide an ice box 25 or refrigerator having a compartment for the ice, in combination with mechanism of a novel construction and arrangement for producing a permanent record of the amount or quantity of ice within the compartment 30 at all times, so that at the end of any given period the user will be provided with a permanent record of the ice consumed.

With the foregoing and various other objects in view we have produced a detailed 35 embodiment of the invention illustrated in the accompanying drawings, in which—

Figure 1 is a vertical sectional view of an ice box or refrigerator illustrating a suitable form of the invention embodied therein.

Fig. 2 is a front elevation partly in section, illustrating the arrangement of the supporting grate or frame upon which the ice is supported within the ice compartment.

Fig. 3 is a detail sectional view, illustrating in plan a suitable arrangement of the lever devices upon which the ice supporting grate or frame is mounted; this view being taken on line 3—3 of Fig. 1.

Fig. 4 is a front view of the indicator device under control of the ice supporting frame or grate for indicating at all times the amount or quantity of ice contained within the ice compartment.

Fig. 5 is a sectional view of the indicating device illustrating the connections for op-

erating the same by the ice support, this view being on the line 5—5 of Fig. 4.

Fig. 6 is a sectional view of the ice box or refrigerator, illustrating a recording device under control of the ice support, whereby a permanent record of the quantity of the ice contained within the ice box during any definite period of time is made.

Fig. 7 is a front elevation, partly in section, further illustrating the construction 65 and arrangement of the mechanism including the recording device.

Fig. 8 is a sectional view, illustrating in plan the arrangement of the lever devices under control of the ice supporting grate 70 or frame, whereby the recording mechanism is operated.

The drawings illustrate an ice box or refrigerator including a compartment 1 for the ice, to which access may be had through 75 a door 2. The ice compartment includes, preferably, a bottom wall 3 provided with a drain passage 4 for well-understood purposes. The bottom wall 3 of the ice compartment is supported below the lower end 80 of the door way 2, so that the mechanism comprising the pivoted levers for supporting the ice grate or frame will be entirely below the lower end of the door way.

Within the compartment 1 are placed two 85 transverse supports 5 adjacent to the front and rear walls respectively, and in such position that they will not obstruct the free discharge of the water from said compartment through the outlet or passage 4. Upon 90 the rear transverse support 5 are placed the rear ends of a bifurcated lever 6, which come together and form a union at a point 7, approximately midway between the supports 5 and between the front and rear walls of 95 the ice compartment.

An arm 8 rises from the union 7 and then extends substantially horizontally toward the front wall of the ice chamber, the support 5 being provided with a space 9 within 100 which the arm 8 is freely movable under weight of the ice. Another bifurcated lever 10 has the extremities of its arms resting upon the support 5, near the front wall of the ice chamber, and the arms of said lever are 105 integrally united at an apex under the rising portion of the arm 8, and the apex of said lever 10 is provided with an extension which is supported by a link 11 pivotally depending from said arm 8.

In the embodiment illustrated in Figs. 1 to 5, the indicating device is supported by a portion of the front wall below the door way 2, in such position that the same may be conveniently observed at any and all times. In the form shown the indicating device includes a casing 12, permanently secured within a proper recess in the front wall portion of the ice chamber, below the door way 2. The indicating mechanism comprises an arbor 13 journaled in bearings in the front and rear walls of the casing 12 and having a pinion 14 affixed thereto and meshing with a rack 15 which is movable in a guide 16. The lower end of the rack 15 is connected to a horizontal element 17, upon each end of which presses a spring 18 of the expansion type. The upper ends of the springs 18 abut against and are retained in proper position by disks 19 connected to the lower ends of the screw-rods 20 which are adjustably supported within the interiorly threaded projections 21 rigid with the upper wall portion of the casing. By adjustment of the devices 19-20, the tension of the springs 18 may be maintained uniform under varying conditions.

The arbor 13 extends through the front wall of the casing and carries an indicator arm 22 which operates adjacent to a graduated scale comprising numerals formed upon the face of the front wall of the casing. These numerals constitute the scale by which the weight or quantity of the ice within the ice chamber is indicated by the position of the indicator arm 22 with respect to the numerals forming the scale. The scale and indicator arm are protected by a transparent window 23 seated and supported within the front portion of the casing at a sufficient distance from the indicator arm to permit free operation and movement thereof.

The casing 12 is formed with an extended portion 24 fitted within an opening in the front wall of the ice chamber. A lever 25 is mounted upon a pivot 26 within the extension 24 and the forward end of said lever is pivotally connected to the member 17, so that by depressing the inner end of said lever the indicator arm 22 will be operated to indicate the weight or pressure exerted upon the lever 25. The inner end of the lever 25 is pivotally united in some suitable manner to the forward end of the arm 8, so that any weight placed upon or supported by the levers 6 and 10 will be accurately indicated by the operation of the indicator arm 22.

The grate or frame for supporting the ice is of novel construction and is combined with the levers 6 and 10 so as to operate and coöperate in a novel manner. Said grate or frame comprises a suitable base 27 in the form of a grate, having its rear portion connected to a vertical supporting member 28

which bears upon the two arms of the lever 6 in proximity to the rear supporting member 5 and its forward portion connected to a vertical supporting member 29 which bears upon the two arms of the lever 10 adjacent to the front supporting member 5. By this arrangement any weight placed upon the supporting base 27 imparts pressure to the levers 6 and 10, thus depressing the forward end of the arm 8 and causing the indicating mechanism to operate.

It will be observed that the grate is in substantially the same plane with the lower wall of the door way 2, so that the ice may be conveniently placed upon the grate without obstruction thereby. Furthermore, the operating mechanism is supported by the lower wall of the ice chamber, but below the lower wall of the door way 2 so that the operating mechanism is completely protected and does not constitute any obstruction against the placing of ice within or removing the same from the ice chamber. In addition the supporting grate 27 with the members 28 and 29 are removable, so that they may be taken out of the ice chamber to afford access to the mechanism supported within the ice chamber, or to the upper surface of the bottom wall 3 of the ice chamber, thus enabling the ice chamber to be kept in proper and clean condition.

While we have illustrated the indicating mechanism supported by the front wall portion of the ice chamber, it will be understood that it may be placed in any other convenient position without departing from any of the broader principles of the invention.

In Figs. 6, 7 and 9 we have illustrated a recording device in connection with the lever devices which are operated by the ice within the ice chamber. The recording devices in this instance comprise a removable, rotating disk 30 supported within a casing 31 and operated by the usual operating mechanism of such devices. The casing 31 is mounted within a suitable recess provided therefor in the front wall portion of the ice box or refrigerator, in such position that the same may be conveniently observed at any time. A recording arm 32 of the usual type operates upon the disk 30 and produces thereon a continuous record to indicate at all times the quantity of ice within the ice chamber. The arm 31 is controlled and moved to different positions in the usual manner by a lever 33, from the inner end of which depends a draft-link 34, the lower end of the draft-link 34 being pivotally connected to a lateral extension 35 integral with the forward end of an arm 36. The arm 36 is integral with the apex of a bifurcated lever 37. The ends of the arms of the lever 37 bear upon a transverse support 38. A coöperating, bifurcated lever 39 has the ex-

tremities of its arms bearing upon a transverse support 40, adjacent to the front wall of the ice chamber, and has its apex supported in a link 41 depending from the arm 5 36, so that with the exception of providing the lateral extension 35, the lever devices are constructed and arranged in substantially the same manner as in the construction illustrated and described in Figs. 1, 2 10 and 3. The grate or frame 42 is connected to front and rear supports 43 bearing upon the arms of the levers 37 and 39 in the same manner that the supports 28 and 29 bear upon the arms of the levers 6 and 10. The 15 grate or frame 42 in this embodiment is also in a plane below the lower wall of the doorway opening into the ice chamber, so that the ice may be conveniently placed within or removed from the ice chamber without 20 interference with or obstruction by the supporting devices. This ice chamber is also provided with a drain passage 44, whereby the water produced by the melting of the ice is conducted out of the ice chamber. 25 While we have illustrated the recording indicating device supported by the upper portion of the wall, it is obvious that it may be supported in any other convenient position. We have not illustrated the mechanism for operating the record disk, for the 30 reasons that the illustration thereof is unnecessary, because of the fact that such operating mechanism is well known and the recording device *per se* is a separate article 35 of manufacture and is available in the market, but the adaptation of the same to our novel operating mechanism constitutes a part of the present invention.

It will also be understood that there may 40 be various modifications and variations in the construction and arrangement of the various parts of the device without departing from the principle and scope of our invention. We do not restrict ourselves to 45 specific features, but what we claim and desire to secure by Letters Patent of the United States, is:—

1. In a refrigerator, an ice chamber having a recess in the front wall thereof and 50 an opening from said recess through the

front wall, an indicating device supported within said recess, a support in said opening, a lever pivoted on said support extending into said recess and operatively connected with the indicating device, levers 55 pivoted within the ice chamber near the front and rear sides thereof, respectively; an arm in connection with the rear lever extending toward the front side of the ice chamber, a connection between said arm and 60 the lever which is pivoted in said opening, whereby said indicating device is operated by said arm, and a filling door hinged to the ice chamber operating independently of said indicating device, whereby the indicating device will indicate the weight of the ice within said chamber as the ice is placed in the chamber.

2. In a refrigerator, an ice chamber having a recess in the front wall thereof and 70 an opening from said recess through the front wall, a filling door hinged to said chamber, scale operating levers pivoted in the bottom of said chamber, an ice supporting grate supported upon said levers 75 approximately level with the bottom wall of the door opening, whereby the ice may be readily slipped into or out of the ice chamber, an indicating device inclosed within said recess, a support within said opening from the recess through the front wall of the ice chamber, a lever pivoted on said support in said opening and extending into said recess and into the ice chamber and being connected with the indicating device, and a connection between said lever and said scale operating levers, whereby said indicating device will be operated to indicate the weight of the ice being placed within the chamber when said door 80 is open.

In witness whereof, we have signed this specification in the presence of two subscribing witnesses.
